UNITED STATES PATENT OFFICE.

WILLIAM A. DOBLE, OF SAN FRANCISCO, CALIFORNIA, ASSIGNEE TO DOBLE LABORATORIES, OF SAN FRANCISCO, CALIFORNIA, A CORPORATION OF CALIFORNIA.

FUEL-CONTROL SYSTEM FOR BURNERS.

1,263,654.

Specification of Letters Patent. Patented Apr. 23, 1918.

Application filed November 28, 1917. Serial No. 204,180.

To all whom it may concern:

Be it known that I, WILLIAM A. DOBLE, a citizen of the United States, and a resident of the city and county of San Francisco, State of California, have invented a certain new and useful Fuel-Control System for Burners, of which the following is a specification.

The invention relates to devices for controlling the flow of fuel to burners, and particularly to burners which include an electric motor in their operating mechanism.

An object of the invention is to provide means for stopping the flow of fuel to the burner when the electric circuit is opened or when the current in the circuit decreases beyond a predetermined value.

A further object of the invention is to provide means for simultaneously opening the fuel line and closing the ignition circuit.

The invention possesses other advantageous features, some of which, with the foregoing, will be set forth at length in the following description where I shall outline in full that form of the invention which I have selected for illustration in the drawing accompanying and forming part of the present specification. In said drawing I have shown one specific form of my invention, but it is to be understood that I do not limit myself to such form, since the invention as expressed in the claims may be embodied in a plurality of forms. In the drawings I have shown my invention applied to a rotary burner in which the fuel is atomized by a rotating element to which the blower for supplying air for combustion is attached, so that both are rotated by the same motor, but it is to be understood that the invention is equally applicable to all types of burners in which an electric motor is used, either to atomize the liquid or to introduce the air for combustion.

Referring to said drawings:

Figure 1 is a partly diagrammatic representation of the fuel control system of my invention applied to a rotary burner.

Fig. 2 is a similar representation of a modified form of the system.

The burner consists of a casing 2 having a rotating element or cup 3 therein for producing a fuel spray, which is driven by the electric motor 4, through the shaft 5. Se-

cured to the shaft below the cup is a blower which is rotated by the motor to induce the necessary air for combustion into the casing. A spark plug 6 or other ignition device is arranged in the casing for igniting the combustible mixture.

Fuel is fed to the burner from the supply tank 7 through the conduit 8, and a pump 9 arranged in the conduit and connected to the shaft 5 operates as a meter to measure the fuel fed to the burner in proportion to the speed of the motor. Means are provided for opening and closing the conduit as the motor circuit is closed and opened.

Arranged in the conduit 8 between the burner and the pump 9 and preferably close to the burner, is a valve casing 12 having an inlet passage 13 and an outlet passage 14, formed at the bottom of the casing. Arranged in the casing is an iron core or plunger 15 provided on its lower end with a valve 16 adapted to seat in and close the outlet passage 14. Connecting the upper end of the valve casing with the conduit 8 on the tank side of the pump is a by-pass conduit 17, and the core 15 is provided on its upper end with a valve 18 adapted to seat in and close the opening of the conduit 17 into the casing. The core 15 is so constructed that the fuel may flow through the casing past the core, either by making the core smaller in diameter than the casing or by providing the core with passages 19. Surrounding the casing is a solenoid 21 which, when energized, raises the core, unseating valve 16 and seating valve 18, permitting the fuel to flow to the burner. When the circuit through the solenoid is opened, the core immediately falls, stopping the flow of fuel to the burner and causing it to flow through the by-pass conduit 17. The solenoid 21 is connected in series with the battery 22, the motor 4 and the control switch 23. Connected in parallel with the motor is a primary circuit containing a make and break device 24 and the inductively connected secondary circuit is connected to the spark plug. 100

When the control switch is closed the motor is started, the fuel conduit 8 is opened and the by-pass closed and the ignition device brought into operation. When the control switch is opened, the supply of fuel to the burner is immediately shut off and the 105

2
 fuel which is subsequently pumped by the pump, due to the momentum of the motor and the cup 3, is diverted through the by-pass conduit. When the burner is used in 5 connection with a steam boiler operating under widely varying loads, as in a motor vehicle, which is provided with means for automatically opening and closing the motor circuit in accordance with variations in 10 boiler conditions, the device of my invention operates to shut off the fuel instantly and thereby permits of a close regulation of boiler conditions.

In Fig. 2 I have shown a construction in 15 which only one valve 16 is employed. The by-pass conduit 17 instead of being connected to the casing 12 at the top, is connected at the bottom below the core 15, so that the by-pass is always open. The outlet passage 14 is controlled by the valve 16 and when the valve is raised, the fuel flows to the burner. When the outlet passage 14 is closed by the valve, the fuel forced into the casing by the pump flows out through 25 the by-pass.

I claim:

1. The combination with a liquid fuel burner, of an electric motor operatively associated therewith, a circuit for said motor, 30 a conduit through which fuel is conveyed to said burner, a pump in said conduit, electrically operated means in said conduit between the burner and the pump and connected to said circuit for controlling the flow 35 of fuel through said conduit and a conduit connecting said means with said first conduit on the intake side of the pump.

2. The combination with a liquid fuel burner, of an electric motor operatively associated therewith, a circuit for said motor, 40 a conduit through which fuel is conveyed to said burner, a pump in said conduit, an electrically operated valve in said conduit between the pump and the burner, and a by-

pass connecting said valve with the conduit 45 on the intake side of the pump.

3. The combination with a liquid fuel burner, of an electric motor operatively associated therewith, a circuit for said motor, a conduit through which fuel is conveyed 50 to said burner, a pump in said conduit, a valve in said conduit, a by-pass connecting said valve with the conduit on the intake side of the pump and a solenoid associated with said valve and connected to said circuit. 55

4. The combination with a liquid fuel burner, of an electric motor operatively associated therewith, a circuit for said motor, a conduit through which fuel is conveyed 60 to said burner, a pump in said conduit, a valve casing in said conduit between the burner and the pump, a by-pass connecting the valve casing with the conduit on the intake side of the pump, a valve in said casing 65 for controlling the flow of fuel to said burner and through said by-pass and a solenoid associated with said valve.

5. The combination with a liquid fuel burner, of an electric motor operatively associated therewith, a circuit for said motor, 70 a conduit through which fuel is conveyed to said burner, a pump in said conduit, a valve casing in said conduit between the burner and the pump, a by-pass connecting 75 the valve casing with the conduit on the intake side of the pump, a valve in said casing adapted in one position to stop the flow of fuel to the burner and in the other position to stop the flow of fuel through the by-pass, 80 and a solenoid associated with said valve and connected to said circuit.

In testimony whereof I have hereunto set my hand at San Francisco, California, this 17th day of November, 1917.

WILLIAM A. DOBLE.

In presence of—

H. G. PROST.
